Attorneys.

UNITED STATES PATENT OFFICE.

MATHEW T. MAHIN, OF GRENO LA, KANSAS.

CORN-SHOCK-COMPRESSING DEVICE.

SPECIFICATION forming part of Letters Patent No. 338,092, dated March 16, 1886.

Application filed August 10, 1885. Serial No. 173,999. (No model.)

To all whom it may concern:

Be it known that I, MATHEW T. MAHIN, a citizen of the United States, and a resident of Grenola, in the county of Elk and State of Kansas, have invented certain new and useful Improvements in Corn-Shock-Compressing Devices; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view showing my improved corn-shock-compressing device applied. Fig. 2 is a similar view of the device. Fig. 3 is a front view of the same, and Fig. 4 is a top view.

Similar letters of reference indicate corresponding parts in all the figures.

My invention has relation to devices for compressing shocks of corn or grain; and it consists in the improved construction and combination of parts of the same, as hereinafter more fully described and claimed.

In the accompanying drawings, the letter A indicates a bar or frame-piece, which has a bearing in its middle, in which bearing the shaft C is journaled, which shaft is tapering, forming a pointed or spit-shaped portion, while its outer end is provided with a drum, E, having a ratchet-wheel, F, at its inner end and a crank, G, at its outer end. A spring-pawl, H, consisting of a flat spring secured at one end upon the upper edge of the frame-piece, engages the ratchet-wheel with the other end, and a lever, I, pivoted at its middle upon the front side of the frame-piece, has an outwardly-bent handle, J, at one end, while its other end may bear against the under side of the spring-pawl and raise the same out of engagement with the ratchet-wheel when the handle is depressed. A pulley, K, is journaled in one end of the frame-piece, and a pulley, L, is journaled in the end of a forwardly-projecting bracket, M, which is secured upon the front side of the frame-piece, and both pulleys are journaled within recesses or slots N and O in the end of the frame-piece and of the bracket, and protected from the outer ends of the recesses or slots by means of guard-strips P and

Q, secured over the open ends of the slots. A cord or chain, R, is secured at one end to the drum, and passes over the pulley at the end of the bracket and over the pulley at the end of the frame-piece, and its other end has an eye, S, which is attached to a hook, T, projecting from the rear side of the opposite end of the frame-piece.

When the device is to be used, the pointed end of the shaft is inserted into the shock to be tied, whereupon the cord is passed around the shock and secured with its eye to the hook, when the shock may be drawn tightly together by winding the cord upon the drum.

The cord may be held drawn by means of the spring-pawl engaging the ratchet-wheel, and the shock may be bound with a wire, cord, or rope made of straw or cornstalks, whereupon the handle end of the pawl-operating lever may be depressed and the pawl disengaged from the ratchet-wheel, allowing the cord to be loosened and unhooked from the hook, whereupon the device may be removed from the finished shock and be applied to another shock, where the operation may be repeated.

By the use of this device shocks of corn or grain, as well as bundles of straw, hay, or other similar material, may easily be compressed, the cord and drum tightening the shock or bundle so that it is not necessary to exert any great strain upon the wire, cord, or rope with which the said shock or bundle is tied.

Having thus described my invention, I claim and desire to secure by Letters Patent of the United States—

In a compressing device for corn-shocks and similar bundles, the combination of a frame-piece having a bearing at its middle, and having a pulley journaled in a slot at one end and guarded by a guard-strip across the end of the slot, and having a hook at the rear side of the other end of the frame-piece, a bracket projecting from the front side of the frame-piece and having a pulley journaled in a slot in the end of the same, and having a guard-strip across the end of the slot, a shaft journaled in the bearing in the frame, and having one end formed into a projecting prong, and having its other end provided with a drum having a ratchet-wheel at its inner end and a crank a

ts outer end, a flat spring-pawl secured at one end to the upper side of the frame and engaging the ratchet-wheel with its other end, a lever pivoted upon the front side of the frame, and having its outer end formed with a handle, and a cord passing over the pulleys and secured at one end to the drum, and having an eye at its other end adapted to engage the hook upon the end of the frame-piece, as and for the purpose shown and set forth.

In testimony that I claim the foregoing as my own I have hereunto affixed my signature in presence of two witnesses.

MATHEW T. MAHIN.
